Primary Examiner — Darlington Ly*Assistant Examiner* — Daniel J Domino(74) *Attorney, Agent, or Firm* — Lorenz & Kopf, LLP(57) **CLAIM**

The ornamental design for a display screen with graphical user interface, as shown and described.

DESCRIPTION

FIG. 1 is a front view of a display screen with graphical user interface showing our new design;

FIG. 2 is a second embodiment thereof;

FIG. 3 is a third embodiment thereof; and,

FIG. 4 is a fourth embodiment thereof.

The dot-dash broken lines showing a display screen and regular broken lines showing elements of the graphical user interface illustrate portions of the article that form no part of the claimed design.

The cross-hatched pattern in the drawings is provided to illustrate areas of color contrast. No color is associated with the cross-hatched pattern. Neither a color nor the actual line pattern form part of the claimed design.
